UNITED STATES PATENT OFFICE.

ANTHONY WARD, OF BROOKLYN, NEW YORK.

WHALE-SHAPED MUSEUM BUILDING.

SPECIFICATION forming part of Letters Patent No. 339,828, dated April 13, 1886.

Application filed June 25, 1885. Serial No. 169,741. (No model.)

To all whom it may concern:

Be it known that I, ANTHONY WARD, of Brooklyn, in the county of Kings and State of New York, have invented a new and useful Improvement in Whale-Shaped Museum Buildings, of which the following is a full, clear, and exact description.

Reference is to be had to the accompanying drawings, forming a part of this specification, in which similar letters of reference indicate corresponding parts in all the figures.

Figure 1 is a sectional side elevation of one of my improved whale-shaped museum buildings, taken through the line *x x*, Fig. 2. Fig. 15 2 is a plan view of the same, partly in section. Fig. 3 is a sectional end elevation of the same, taken through the line *y y*, Fig. 1. Fig. 4 is a similar sectional view as Fig. 1, with portions broken away and the lower jaw partially 20 elevated.

The object of this invention is to provide museum buildings constructed to represent a whale having a movable lower jaw to admit spectators and provided with gravity-cars to 25 carry them out.

The invention consists in the construction and combination of the various parts of the museum building, as will be hereinafter fully described and claimed.

30 A represents the museum building, which is made in the form of a whale with a stationary upper jaw, B, having stationary teeth C, and with a movable lower jaw, D, having movable teeth E.

35 The movable lower jaw, D, is attached to a vertical rack-bar, F, the teeth of which mesh into the teeth of the pinion-wheel G, attached to a horizontal shaft, H. The shaft H is placed in a small chamber below the main chamber 40 and revolves in bearings attached to the frame of the building. To the shaft H is attached a spool or drum, I, to which is attached and around which is wound a rope or chain, J.

45 The other end of the rope or chain J is attached to and wound around a spool or drum, K, journaled to supports placed within the main chamber, and which is provided with a crank, L, by means of which the said drum K is turned to wind up the rope or chain J and 50 close the lower jaw, D. The lower jaw can be arranged to open by its own weight when the rope or chain J is slackened, or it can be

opened by turning the shaft H by means of a crank or hand-wheel, M, attached to the end of the said shaft.

55 The lower jaw, D, is made to move up and down vertically by means of guide-rods N, attached to the platform O, over which the spectators pass in entering the main chamber, and which is secured to the upper end of the rack-bar F. The guide-rods N pass through and slide in guide-holes in cross-bars P of the frame of the building and support the lower jaw, D, when fully lowered.

60 The teeth E of the lower jaw, D, are connected with the ends of springs Q, attached at their centers to supports secured to the frame of the building. To the ends of the springs Q are attached the ends of the cords or chains R, which pass around guide-pulleys S, pivoted to 70 supports secured to the middle part of the rack-bar F. From the pulleys S the cords or chains R pass over guide-pulleys T, pivoted to supports secured to the floor-timbers of the main chamber or other suitable supports, and 75 their ends are secured to the forward ends of the spiral springs U, the rear ends of which are secured to the frame-timbers of the main chamber.

80 With this construction, as the lower jaw, D, is raised, the cords or chains R will be slackened, and the teeth E will be raised above the platform O by the springs Q, so as to come into view and engage with the teeth C of the upper jaw, B, when the lower jaw, D, is fully 85 raised.

85 When the lower jaw, D, is lowered, the cross cords or chains R will be tightened and the teeth E will be drawn down below the level of the platform O, so as to be out of the way of 90 people entering the museum.

95 The mouth of the whale, except in front, is surrounded by a fence or railing, V, to prevent people from entering the said mouth at its sides.

The curiosities to be exhibited are to be placed in cases W arranged within the main chamber, or are suspended from the walls of the said chamber. In the sides of the rear part of the main chamber are formed openings 100 with which are connected exit-passages X.

In the rear part of the main chamber is placed an inclined track, Y, upon which is placed a car, Z, and which passes out through

an opening below or in the tail of the whale, so that the said car Z, by its own weight, can carry out the spectators who may prefer that method of exit. The car Z is drawn in after 5 its passengers have alighted by a rope or chain, a, one end of which is attached to the said car, and its lower end is attached to the drum of a windlass, b.

The opening through which the car Z passes 10 out and in is closed by a trap-door, c, secured to the tail of the whale or forming a part of the said tail, and may be opened and closed by the movement of the said car Z, or by other suitable means.

15 Access is had to the raised inner end of the track Y by stairs d or other convenient means.

The sides of the part of the track Y within 20 the main chamber are protected by a railing, e, to prevent passengers from falling or being pushed off the said track, and to prevent the spectators from getting upon the said track at any other place than its upper end.

In the back of the whale are formed one or 25 more ventilating-openings, f, provided with caps g, to allow foul air to escape.

Above the back of the whale are placed 30 finely-perforated pipes h, which are connected with water-pipes i, so that a fine spray of water can be constantly showered upon the back of the whale to keep the main chamber cool.

Having thus described my invention, I claim as new and desire to secure by Letters Patent—

1. A museum building made, substantially

as herein shown and described, in the shape of a whale, and provided with a movable lower 35 jaw to form an entrance-passage, as set forth.

2. In a whale-shaped museum building, the combination, with the stationary upper jaw, B, and the movable lower jaw, D, of the platform O, the rack and pinion F G, the cord or 40 chain J, and the drums I K, having cranks M L, substantially as herein shown and described, whereby the said lower jaw can be readily closed and opened, as set forth.

3. In a whale shaped museum building, the 45 combination, with the movable lower jaw, D, the platform O, the rack-bar F, and the stationary upper jaw, B, having teeth C, of the movable teeth E, the springs Q, the cords and guide-pulleys R S T, and the springs U, substantially as herein shown and described, whereby the said teeth will be projected above and withdrawn below the said platform automatically as the said movable jaw is raised and lowered, as set forth. 50

4. The combination, with a whale-shaped museum building having an exit-opening in its tail, of the inclined track Y, the car Z, and the rope and windlass a b, substantially as herein shown and described, whereby the spectators can be carried out by gravity and the said car readily drawn back, as set forth. 55

ANTHONY WARD.
